DESIGN FOR A SANDAL

Herman Buraglia, Boston, Mass.

Application October 8, 1935, Serial No. 58,881

Term of patent 14 years

To all whom it may concern:

Be it known that I, Herman Buraglia, a citizen of the United States, residing at Boston, in the county of Suffolk and State of Massachusetts, have invented a new, original, and ornamental Design for Sandal, of which the following is a specification, reference being had to the accompanying drawing, forming part thereof.

Figures 1, 2 and 3 are top plan, side, and front end elevational views, respectively, of a sandal showing my new design.

I claim:

The ornamental design for a sandal, as shown.

HERMAN BURAGLIA.
